US00D327711S

United States Patent [19]

Heinhold

[11] Patent Number: Des. 327,711

[45] Date of Patent: ** Jul. 7, 1992

[54] GAME BOARD

[76] Inventor: William Heinhold, #10-6 Loconder Drive, Hamilton, Ontario, Canada, L8W-1V8

[**] Term: 14 Years

[21] Appl. No.: 501,190

[22] Filed: Mar. 29, 1990

[52] U.S. Cl. D21/17; D21/26

[58] Field of Search D21/14-36; 273/236-285

D. 311,034 10/1990 La Riviere D21/26

Primary Examiner—Bernard Ansher

Assistant Examiner—Sandra Morris

Attorney, Agent, or Firm—Leon Gilden

[57] CLAIM

The ornamental design for a game board, as shown and described.

DESCRIPTION

FIG. 1 is a front elevational view of a game board showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof, the broken line showing of the game pegs is for illustrative purposes only, and forms no part of the claimed design.
